US0D1038756S

(12) **United States Design Patent** (10) **Patent No.:** **US D1,038,756 S**
(45) **Date of Patent:** **** Aug. 13, 2024**

(54) **SCREW CAP**

(71) Applicant: **Blue Ocean Closures AB**, Karlstad (SE)

(72) Inventor: **Lars Sandberg**, Hammarö (SE)

(73) Assignee: **BLUE OCEAN CLOSURES AB**, Karlstad (SE)

(**) Term: **15 Years**

(21) Appl. No.: **35/516,447**

(22) Filed: **Dec. 2, 2022**

(80) **Hague Agreement Data**

Int. Filing Date: **Dec. 2, 2022**

Int. Reg. No.: **DM/226856**

Int. Reg. Date: **Dec. 2, 2022**

Int. Reg. Pub. Date: **Mar. 3, 2023**

(51) **LOC (14) Cl.** **09-07**

(52) **U.S. Cl.**

USPC **D9/453**

(58) **Field of Classification Search**

USPC D9/434–436, 499, 440, 443, 447, 449,
D9/454, 452, 453; D7/392.1, 396.2
CPC A61J 1/1406; A61J 1/1425; A61J 1/1487;
B65D 47/0804; B65D 47/2031; B65D
50/046
